UNITED STATES PATENT OFFICE.

CHARLES W. BECK, OF DETROIT, MICHIGAN, ASSIGNOR TO THE BECK-FROST CORPORATION, OF DETROIT, MICHIGAN, A CORPORATION OF MICHIGAN.

STEERING WHEEL.

Application filed April 21, 1924. Serial No. 708,058.

This invention relates generally to steering wheels for motor vehicles, boats and the like and refers more particularly to wheels of the built-up type wherein the spider portion is operatively connected to the hub piece by means of a suitable lock.

One of the essential objects of the invention is to provide a wheel of this type having a simple form of lock which is preferably carried by the spider portion of the wheel and is provided with a locking bolt that is adapted to be moved by a suitable key into engagement with the hub piece for operatively connecting the spider portion thereto, or moved out of engagement with the hub piece for rendering the steering wheel inoperative.

Another object is to provide a strong and durable wheel which is built up in such a way that any maliciously inclined person will be effectively prevented from removing the spider portion of the wheel from the hub piece or the lock from the spider portion in an attempt to turn the hub piece to steer the vehicle.

With the above and other objects in view the invention consists in certain novel features of construction, combinations and arrangement of parts as will be more fully described and particularly pointed out in the appended claims.

In the accompanying drawing:

Figure 1 is a fragmentary top plan view of a steering wheel embodying my invention;

Figure 2 is a sectional view taken on line 2-2 of Figure 1;

Figure 3 is a sectional view taken on line 3-3 of Figure 2.

Referring now to the drawing in which like characters of reference designate corresponding parts throughout the several views, the numeral 1 designates a rim preferably of wood secured to a metallic spider 2 which preferably includes a plurality of radially extending arms 3 and a head 4, the latter preferably surrounding a metal hub piece 5 and having laterally extending projections 6 at its upper end supporting the arms 3.

The arms 3 are preferably formed from one sheet of metal and are preferably detachably secured to the rim by means of suitable screws, while the head 4 is preferably a malleable casting and is provided upon its

lower face with a marginal beading 7. For securing the head 4 to the arms 3, the latter are preferably provided with the connecting depending flanges 8 and 9 respectively. As shown, the flanges 8 are preferably crimped over the marginal beading 7 of the head, while the flanges 9 are curved inwardly so that they embrace the end portions of the projections 6.

In order that the spider 2 may rotate about the hub piece 5 without any likelihood of being removed therefrom, the hub piece is preferably provided with an annular shoulder 10 that forms a bearing for the lower end of the head 4, and is provided at its upper end with an over-hanging portion 11 that engages a countersunk portion 12 in the upper face of a plate 13 which preferably rests in the cooperating depressed inner end portions 14 of the arms 3.

For locking the spider portion 2 to the hub piece 5, I preferably provide a vertical locking bolt 15 having a horizontal laterally extending shank 15' that is preferably slidably mounted in a slot 16 formed in a radial extension 17 of the head 4 and is adapted to be projected into a recess 18 in the hub piece 5 by means of an eccentric pin 19 extending downwardly from a rotatable cylinder 20 of a suitable tumbler lock 21. As shown the extension 17 is preferably formed integral with the lower face of one of the projections 6 and is provided with a vertical recess that receives the lock casing 22. This casing preferably extends upwardly through the projection 6 and abuts the lower face of the adjacent arm 3, while the rotatable cylinder 20 preferably extends through a suitable opening 23 in the arm and is provided at its upper end with a suitable key opening 24.

To prevent removal of the lock from the spider portion 2 of the wheel, I preferably provide a suitable pin or plug 25 that is driven through a suitable opening in the extension 17 into a cooperating socket in the lock casing 22 and is filed off flush with the outer surface of the extension so that it cannot be readily removed.

In use, the proper key may be inserted into the opening 24 to operate the lock mechanism for releasing the lock cylinder 20 so that the latter may be turned by the key to move the bolt 15 into locking engagement with the recess 18 in the hub 110

July 6, 1926.
